Primary Examiner — Eric L Goodman*Assistant Examiner* — John R Yeh(74) *Attorney, Agent, or Firm* — Trueba & Suarez PLLC;
William R. Trueba, Jr.; Roberto M. Suarez(57) **CLAIM**

The ornamental design for an end cap for a mop stick, as shown and described.

DESCRIPTION

FIG. 1 is a perspective top view of an end cap for a mop stick;

FIG. 2 is a top view of an end cap for a mop stick;

FIG. 3 is a bottom view of an end cap for a mop stick;

FIG. 4 is a right-side view of an end cap for a mop stick;

FIG. 5 is a left-side view of an end cap for a mop stick;

FIG. 6 is a front view of an end cap for a mop stick; and,

FIG. 7 is a back view of an end cap for a mop stick.
